UNITED STATES PATENT OFFICE.

CHARLES W. WEISS, OF BROOKLYN, NEW YORK, ASSIGNOR TO THE WEISS MANUFACTURING COMPANY, OF SAME PLACE.

ELECTROPHORUS FOR IGNITING GAS.

SPECIFICATION forming part of Letters Patent No. 307,823, dated November 11, 1884.

Application filed November 23, 1883. (No model.)

To all whom it may concern:

Be it known that I, CHARLES W. WEISS, a citizen of the United States, and a resident of Brooklyn, Kings county, New York, have 5 invented certain Improvements in an Electrophorus for Igniting Gas, of which the following is a specification.

My invention relates to that class of gas-lighting apparatus wherein an electric spark 10 is produced by friction between a resinous and a metal plate.

The novel features of the invention relate in part to the particular metal I employ to form a frictional surface for the resinous plate to 15 impinge upon and move over, and in part to the peculiar construction of the apparatus, all as will be hereinafter more fully set forth.

In the drawings, which serve to illustrate my invention, Figure 1 is a vertical mid-section 20 of the apparatus shown as mounted fixedly on a gas bracket or tip. Fig. 2 is a front view of the same. Fig. 3 is a plan. Figs. 4, 5, and 6 are fragmentary sectional views illustrating modifications. These will 25 be particularly described hereinafter.

I have herein shown my apparatus as connected with a gas tip or burner adapted to be screwed onto the bracket where the ordinary tip is now attached. This, however, is not 30 absolutely necessary, as my electrophorus may be applied to a torch for lighting.

A represents an ordinary burner-tip, and B a pipe which screws onto the gas-bracket. To this pipe the electrophorus is attached. The 35 latter comprises a box or case, whereof *a* is the metal front plate, *b* the metal back plate, and *c* a drum or hoop of some insulating material—as hard rubber or glass. I have shown the metal plates *a* and *b* as screwed directly 40 onto the drum *c*, but they may be attached in any good way. On the inner face of the back plate, *b*, is mounted, by preference, a layer of some soft fabric—as muslin or leather—*d*, and on this fabric is mounted a plate of lead, *e*, to 45 provide a frictional surface to receive the resinous plate. This latter plate, *g*, is made, by preference, from hard rubber, and it is attached to an axial metal stem, *h*, which passes through a stuffing-box in the front plate, *a*, 50 and its outer end is provided with a cross-

handle or thumb-piece, *i*, by which the resinous plate is rotated and lifted. The resinous plate *g* is held in contact with the leaden plate *e* by means of a spring, *j*, of any kind, arranged between the said plate *e* and the plate *a* of 55 the case; and in order that the plate *g* may be first rotated slightly and then lifted from the lead plate by one rotatory operation of the thumb-piece *i*, I provide a hollow plug, *k*, which screws into the aperture in the front 60 plate, *a*, onto a suitable packing, *l*, thus forming a stuffing-box for the stem *h*. The thumb-piece *i* rests, normally, between two inclined projections or cams, *m m*, on or forming a part of the plug *k*. One side of these is inclined 65 and the other side is perpendicular. Therefore when the thumb-piece *i* is turned, the first movement is simply that of rotation; but when the lower faces of the piece *i* strike the inclined faces of the projections *m m*, the rotation continues; but the thumb-piece rides up the inclines, lifts the resinous plate from the lead plate, and compresses spring *j*. A continuation of the rotation causes the thumb-piece to pass over the cams *m*, when the spring 70 draws it back to its normal position. (Shown in Fig. 2.) In Fig. 3 the thumb-piece is shown partly turned around and riding up the inclines on *m*.

In applying my device for igniting the gas, 80 the spark is produced between the metallic points *n* and *o*, arranged over the burner-tip or nipple *A*. The former is attached to the back plate, *b*, and is electrically connected with this plate and the lead friction-plate thereon, 85 and the latter, *o*, is attached to the pipe *B*, and is electrically connected with the resinous plate *g* and the ground through the various conducting parts. The flanged foot of the stem *h* is connected to the resinous plate *g* by metal screws or rivets *p*, and these are relied on to form the necessary metallic connection between plate *b* and the earth. Other means may, however, be provided for this purpose. It is not necessary that the gas be 90 turned on by the same means that produces the spark. The gas-cock may be entirely separate and the gas be turned on before the spark is produced; but for convenience I prefer to employ the means I will now describe, 95 100

or some equivalent device, for turning on the gas and producing the spark by one movement, and nearly simultaneously.

Referring to Figs. 1 and 2, *q* represents the 5 gas-passage in *B*, (shown in dotted lines,) leading to the burner *A*, and *r* an ordinary gas-cock with a thumb-piece, *s*. Projecting parts 10 *t* on the thumb-piece *i* contact with the wing of the thumb-piece *s*, and the first movement 15 of *i* serves to turn the gas-cock so as to let on a little gas. The further movement of *i*, as before described, produces the spark and ignites the gas. The latter may now be turned on full-head, if desired.

15 As I have said, one very important feature of my invention is the employment of the metal, lead, for the frictional plate on the insulated metal plate *B* of the electrophorus. Heretofore, so far as I am aware, this metal 20 has not been employed for this purpose. Usually the metal plate has been covered with leather to form a frictional surface for the resinous plate to impinge on and play over. I find that by employing lead for this purpose 25 I am enabled to produce the necessary spark with a circular plate of one inch diameter, while with a leather or other metal surface the plate must be much larger—say four inches in diameter. Tin-foil containing considerable lead answers tolerably well, but its 30 value increases with the lead it contains. I find pure lead to be the best and to possess distinct characteristics.

In order that the resinous plate may adjust 35 itself to the lead plate, I usually back the latter, as shown in Fig. 1, with a layer of some soft material, which serves as a sort of cushion; but I may secure the lead directly to the back plate, *b*, as shown in Fig. 4, and dress its 40 face off truly to fit the resinous plate; or I may also make the entire back plate, *b*, of lead, as shown in Fig. 5. I prefer, however, to make the back plate of some harder metal.

The frictional faces of the resinous and lead 45 plates may be plane, as shown, or may be concavo-convex, as shown in Fig. 6, if desired. It is only important that the frictional surfaces should contact to the fullest extent possible.

In lieu of the projections *t* on the thumb-piece *i* of the gas-cock, any portion of said 50 thumb-piece may be made to engage the thumb-piece on the gas-cock.

The details of construction connected with the operation of the gas-burner, &c., are not claimed herein, as they form the subject-matter 55 of a separate application filed as a division hereof March 12, 1884, and having the Serial No. 123,951.

I claim as my invention—

1. An electrophorus the metallic plate of 60 which has a frictional surface of lead or lead alloy for the resinous plate to impinge against, substantially as set forth.

2. An electrophorus having a yielding frictional surface of lead or lead alloy for the resinous plate to impinge against, substantially as 65 described.

3. An electrophorus in which the frictional surface of the metallic or positive plate is mounted upon or supported by a flexible or 70 yielding substance or material, substantially as and for the purpose described.

4. An electrophorus the metallic plate of 75 which is provided with a frictional plate of lead or lead alloy, and a cushion of some soft material, as cloth or leather, interposed between the frictional plate and the said metallic plate, substantially as set forth.

5. In an electrophorus, the combination, 80 with the hermetically-sealed case, of the two generating-plates inclosed therein, one consisting of a metallic plate having a surface of lead or lead alloy, and the other a plate of vulcanized rubber attached by means of metallic screws to a metal plate forming a back- 85 ing, together with means for operating the said plates from the outside of the case, substantially as described.

In witness whereof I have hereunto signed my name in the presence of two subscribing 90 witnesses.

CHARLES W. WEISS.
